UNITED STATES PATENT OFFICE.

SIDNEY A. GRANT, OF SPRINGFIELD, MASSACHUSETTS.

FEEDING ATTACHMENT FOR PRINTING-PRESSES.

SPECIFICATION forming part of Letters Patent No. 249,755, dated November 22, 1881.

Application filed January 31, 1881. (No model.)

To all whom it may concern:

Be it known that I, SIDNEY A. GRANT, a citizen of the United States, residing at Springfield, county of Hampden, and State of Massachusetts, have invented new and useful Improvements in Envelope-Feeding Devices for Printing-Presses, of which the following is a specification.

This invention relates to the details of construction of an endless feed apron or belt and an envelope-feed box, both adapted to be applied to and used with an ordinary printing-press, the object being to provide an improved feeding device to be used with a printing-press for printing upon the face of envelopes, whereby envelopes are automatically taken from a feed-box, in which a file of them is placed, carried between the bed and platen of said press, where they receive a printed impression and are conveyed from there to any convenient receptacle provided for receiving the printed envelopes.

In the drawings forming part of this specification, Figure 1 is a side elevation of a printing-press—such as Kidder's patent, February 10, 1880, No. 224,440—having applied thereto my improved envelope-feeding devices. Fig. 2 is an isometric view of the endless feed apron or belt and the feed and guide rollers of the press, all shown detached from the latter.

A is the bed of the printing-press.

B is the platen.

d e are feed-rollers adapted to be rotated intermittently by any well-known devices.

1 2 3 4 5 6 7 are guide-rolls in the press, over which the apron runs.

i is an envelope-feed box.

o is a narrow bottom plate, partially covering the bottom of the feed-box i.

a is a series of envelopes, piled flatwise in box i, and shown through the broken-away side of said box in Fig. 1.

v are envelopes riding upon and carried by the apron.

b is an endless apron or belt adapted to be moved intermittently around a printing-press upon proper feed and guide rolls, and is provided with one or more series of lips, x, formed or arranged in longitudinal lines upon or in said apron by cutting around three sides of said

lips, as shown, or otherwise, so that each lip will be practically over an opening in the apron. I construct the apron b of thin flexible metal or other suitable material, making cuts therein, as shown, to disengage the lips x therefrom around three of their sides, so that their freed edges may be sprung away from the plain face of the apron when the latter moves over certain rollers, as and for the purpose hereinafter stated, and spring back again when that portion of the apron has passed by said rollers, as shown at rollers 4 and 5 in Fig. 2, and between rollers 5 and 6, same figure, and in Fig. 1 at rollers 4, 5, and 1. The said series of lips x may be formed in a single longitudinal line in said apron or more. Apron b is mounted upon the rollers 1 2 3 4 5 6 7 of a printing-press and passes between the feed-rollers d e thereof, which roll closely upon each side of the apron and draw it between them. In addition to said means for moving said apron, the latter has pierced in one edge thereof a series of pin-holes, as shown in Fig. 2, and upon roller d is set a series of pins, 8, which enter said pin-holes as the apron passes between said rollers, and thus the apron is compelled to obey the movements of said rollers.

The feed-rollers d and e have an intermittent rotary motion given to them by the press through such devices as are shown, or other similar ones.

The envelope-feed box i is supported in an inclined position on a part of the press, as shown, and has a narrow bottom, o, partially covering its lower end, and the open or uncovered portion thereof is over that part of the apron b which runs over roller 5, and is over one of the lines of lips x in said apron. When more than one line of said lips is formed in said apron a feed-box, i, is provided for each line thereof.

The operation of my improved feed devices is as follows: A pile of envelopes with their seal-flaps down is placed in the feed-box i, and when so placed therein will rest in the position shown in Fig. 1. It will be seen that that portion of the seal side of the envelopes below the seal-flaps is over the narrow bottom o of said feed-box; but the weight of the pile and

the natural inclination of a seal-flap to spring off causes the seal-flap of the bottom envelope of the pile as they are removed one by one to spring down away from the under face of the envelope, and the pressure of the narrow bottom *o* upon that part of the bottom envelope to one side of the seal-flap contributes to make the flap of said envelope spring off, as above described. The printing-press is set in motion and the movements of the platen and the intermittent movements of the apron *b* are "timed" so that each time the apron stops the platen *B* moves toward the bed *A* to produce an impression. As said apron *b* moves around the press and over roller 5 under the feed-box *i*, each lip *x* as it goes over said roller springs out, as shown at rollers 4 and 5, and as it moves under the pile *a* of the envelopes in box *i* it hooks under the seal-flap of the bottom one and draws it out from under the said box and carries it along over the bed of the press, where it is printed upon, and thence over back of the same, where it is removed or drops from the apron as it passes over roller 1, which causes the lip *x* to spring out and free it.

Another and great advantage gained by the operation of a feed-apron constructed as is that herein shown and described is that the lips *x* carrying the envelope is interposed between the flap thereof and the front side of the envelope, which receives the printed impression, and forms a plain even surface or backing for the envelope when it is printed upon, and obviates the inconveniences arising from printing upon the face of the envelope when the seal-flap lies directly under it. A further advantage is that each envelope is held absolutely in proper position, with no tendency to assume an angle to the bed.

It is obvious that lips to serve the purpose 40 of the lips *x*, herein shown and described, may be secured upon the face of an endless apron similar to apron *b* by soldering or otherwise securing said lips to the face of an apron by one edge; but this modification would be objectionable, because it would not leave the apron of one uniform thickness throughout, and would be liable to cause inconvenience in the operation of the feed-rolls.

What I claim as my invention is—

1. The combination, with a box, *i*, adapted to hold a series of envelopes with their flaps downward, and with a printing bed and platen, of an apron traversing between said bed and platen and below said box, and provided with lips *x*, constructed and arranged as described, to catch the envelope-flaps, and appliances whereby said apron is moved intermittently to retain each envelope in a fixed position while being printed, as set forth.

2. In an envelope-feeding device for printing-presses, the combination of the endless apron *b*, provided with the lips *x*, projecting at an angle therefrom over openings therein, the feed-box *i*, having a partially-closed bottom, and of appliances, substantially as described, for imparting to said apron an intermittent motion in one direction under said feed-box and across the platen *A* of the printing-press, substantially as and for the purpose set forth.

SIDNEY A. GRANT.
